UNITED STATES PATENT OFFICE

LOUIS V. ARONSON, OF NEWARK, NEW JERSEY, ASSIGNOR TO ART METAL WORKS, INC.,
A CORPORATION OF NEW JERSEY

DESIGN FOR A PYROPHORIC LIGHTER OR SIMILAR ARTICLE

Application filed May 9, 1929. Serial No. 31,145. Term of patent 14 years.

To all whom it may concern:

Be it known that I, LOUIS V. ARONSON, a citizen of the United States, residing at Newark, in the county of Essex and State of New Jersey, have invented a new, original, and ornamental Design for a Pyrophoric Lighter or Similar Article, of which the following is a specification, reference being had to the accompanying drawing, forming part thereof, wherein—

Figure 1 is a plan view of the pyrophoric lighter;

Fig. 2 is a side elevational view of said pyrophoric lighter;

Fig. 3 is an end elevational view of said pyrophoric lighter; and

Fig. 4 is a bottom view of said pyrophoric lighter.

On Figs. 2 and 3 of the drawing, the irregular cross-hatching represents an ornamental finish.

I claim:

The ornamental design for a pyrophoric lighter or similar article substantially as shown and described.

LOUIS V. ARONSON.
